(57) **CLAIM**

The ornamental design for a filter member for filtering irrigation water, as shown.

DESCRIPTION

FIG. 1 is a first perspective view of the filter member for filtering irrigation water showing my new design.

FIG. 2 is a second perspective view of the filter member for filtering irrigation water showing my new design.

FIG. 3 is a front view of the filter member for filtering irrigation water showing my new design.

FIG. 4 is a side view of the filter member for filtering irrigation water showing my new design.

FIG. 5 is an enlarged top view of the filter member for filtering irrigation water showing my new design; and,

FIG. 6 is an enlarged bottom view of the filter member for filtering irrigation water showing my new design.
